THERMAL COPIER

Heinz E. Hertel, Mt. Prospect, and Robert L. Kearney,
Northbrook, Ill., assignors to Bell & Howell Company,
Chicago, Ill., a corporation of Illinois

Filed June 6, 1969, Ser. No. 17,562

Term of patent 14 years

Int. Cl. D16—05

U.S. Cl. D61—1

Fig. 2.

Fig. 3.

Fig. 4

FIG. 1 is an isometric view of a thermal copier, embodying our new design.

FIG. 2 is a front elevational view of the design shown in FIG. 1.

FIG. 3 is a side elevational view of the design showing the side hidden in FIG. 1.

FIG. 4 is a rear elevational view of the design shown in FIG. 1.

The bottom panel is unornamented and is generally rectangular in configuration as will be apparent from an inspection of FIGS. 2, 3 and 4.

We claim:

The ornamental design for a thermal copier, as shown and described.
